UNITED STATES PATENT OFFICE

168,102

BOX FOR CONTAINING CONFECTIONS

Adolph Matzen, Tacoma, Wash.

Application June 28, 1952, Serial No. 20,401

Term of patent 14 years

(Cl. D58—11)

To all whom it may concern:

Be it known that I, Adolph Matzen, a citizen of the United States of America, residing at Tacoma, in the county of Pierce and State of Washington, have invented a new, original, and ornamental Design for a Box for Containing Confections, of which the following is a specification, reference being had to the accompanying drawing, forming a part thereof.

In the drawing:

The single figure is a perspective view of a container for confections showing my new design, wherein the rear and side views not shown are the same as those shown.

The dominant feature of my design resides in the portions shown in full lines in the drawing.

I claim:

The ornamental design for a box for containing confections, as shown and described.

ADOLPH MATZEN.
